(57) **CLAIM**

The ornamental design for a stereotactic apparatus, as shown and described.

DESCRIPTION

FIG. 1 is perspective view from one side of a stereotactic apparatus embodying the present invention;

FIG. 2 is a perspective view from the opposite side from FIG. 1 of said stereotactic apparatus;

FIG. 3 is a side view of said stereotactic apparatus;

FIG. 4 is a front view of said stereotactic apparatus;

FIG. 5 is a side view opposite from FIG. 3 of said stereotactic apparatus;

FIG. 6 is a rear view of said stereotactic apparatus;

FIG. 7 is a top view of said stereotactic apparatus; and,

FIG. 8 is a bottom view of said stereotactic apparatus.
